G. D. Sidway,

UNITED STATES PATENT OFFICE.

GILBERT D. SIDWAY, OF JACKSON, MISSISSIPPI.

BANANA-CARRIER.

SPECIFICATION forming part of Letters Patent No. 376,555, dated January 17, 1888.

Application filed July 18, 1887. Serial No. 214,668. (No model.)

To all whom it may concern:

Be it known that I, GILBERT D. SIDWAY, a citizen of the United States, residing at Jackson, county of Hinds, State of Mississippi, have invented a new and useful Case for Carrying Bananas and Similar Fruit, of which the following is a specification, reference being had to the accompanying drawings, forming part thereof.

10 My invention relates to a case for the carrying and handling of bananas which will protect them from injury and enable them to be more easily handled, stored, and transported than they now are.

15 In the drawings, Figure 1 is a plan view; Fig. 2 a perspective view, and Fig. 3 a plan view of a modification.

I attain these objects by placing the butt-end or shank of the banana-stalk in a V-shaped slot, B, made in a board, A. This board may be of one piece, with the slot cut in it, or it may be of two pieces so placed as to leave a V-shaped opening between them. This board A forms the top of the case. The 20 bottom of the case is a similar board, C, without the slot or opening. The sides of the case are made by slats E of the proper length to hold the bunch of fruit and of sufficient strength to support its weight when it is 25 hanging downward from the slot in the top board, A, as the case is set on end.

The end of the banana-stalk is placed in the slot and forced as far as it will go toward the

narrower end of the slot. This will hold up the banana-bunch as long as it stays caught in the converging end of the slot. To secure it from slipping to the wider end of the slot a key, D, shaped like a triangle, (almost any shape will answer for a key,) is nailed or otherwise fastened to the top of A, but so loosely 35 that one end of it can be moved across the V-shaped slot. After pressing it (the key) firmly against the banana-stalk from the broad end of the slot it is secured there by a nail, or in some other firm manner. This key D may be 40 made in the shape of a half-eccentric wheel and used as above stated.

The case containing the banana-bunches may now be stood up on end and packed in cars, wagons, or warehouses, &c., and carried 45 about without bruising or blemishing the fruit, so producing black and rotten spots and spoiling its sale.

One or more of these cases may be made in combination for carrying more than one bunch 50 at a time.

I claim and ask Letters Patent for—

A banana-case made with the top board, A, with the V-shaped slot or opening B, the bottom board, C, side boards, E, and the key D, 55 to be used for carrying bananas and similar fruit, substantially as above set forth.

G. D. SIDWAY.
